By his Attorneys:-

Albion & Co.

UNITED STATES PATENT OFFICE.

RICHARD J. NEWMAN, OF NORWICH, KANSAS.

CUFF-HOLDER.

SPECIFICATION forming part of Letters Patent No. 394,206, dated December 11, 1888.

Application filed August 18, 1888. Serial No. 283,112. (No model.)

To all whom it may concern:

Be it known that I, RICHARD J. NEWMAN, a citizen of the United States, residing at Norwich, in the county of Kingman and State of 5 Kansas, have invented a new and useful Improvement in Cuff-Holders, of which the following is a specification.

The object of this invention is to provide a simple, cheap, durable, easily-operated, and 10 secure cuff-holder, which may be applied to any cuff and will hold the same in the desired position without danger of being detached.

The invention consists in a certain novel 15 construction and arrangement of parts, fully set forth hereinafter in connection with the accompanying drawings, and specifically pointed out in the appended claims.

In the drawings, Figure 1 is a view of the 20 holder applied in the operative position to a cuff. Fig. 2 is a central sectional view of the same, showing the manner of attaching the cuff to the band of the shirt. Fig. 3 is a detail perspective view of the holder.

Referring by letter to the drawings, A designates a cuff, in the outer button-hole of 25 which is arranged the cuff-button B, and C designates the wristband, Fig. 2, of the shirt, (not shown,) in the button-holes of which is arranged the shirt-button D.

E designates the holder, which consists of 30 the plate F, provided at its outer end with a notch, f, engaging the shank of the cuff-button, and bent upon itself at its inner end to form the arm G, which is provided with a central longitudinal slot, g.

A swinging button, H, is connected by a 35 loose link, I, to the inner end of the plate on the opposite side to the slotted arm.

The holder is applied to the cuff by engaging 40 the notch in the end of the main plate with the shank of the cuff-button and engaging the swinging button in the inner button-holes of the cuff. It will be seen that in this

position the slotted arm extends outwardly, with the open end of the slot at the free end 45 of the arm.

To apply the cuff to the shirt, pass the former over the sleeve of the latter, and after engaging the open end of the slot in the arm with the shank of the sleeve-button draw the 50 cuff outward until it is checked by the inner end of the slot striking against the shank of the sleeve-button. To remove the cuff from the shirt, draw the former backward until the slot is disengaged from the sleeve-button, and 55 then, after turning the cuff, draw it outward.

The advantages of this invention will be 60 readily appreciated. The holder is entirely concealed within the cuff, and therefore cannot catch the coat or other garments. The 65 cuff cannot be detached by a direct outward pull. The shirt is not engaged, and therefore cannot be torn or injured by a strain on the cuff.

Having described my invention, I claim— 65

1. In a cuff-holder, the main plate provided 70 with a notch at one end to engage the outer cuff-button and a button to engage the inner button-holes of the cuff, and the slotted arm to engage the sleeve-button, substantially as 75 specified.

2. The herein-described cuff-holder, comprising the main plate provided at its outer 75 end with a notch, f, and bent upon itself at its inner end to form the arm G, which is provided with a longitudinal slot, g, and the loose button mounted on the inner end of the main plate to engage the inner button-holes of the cuff, substantially as specified.

In testimony that I claim the foregoing as 80 my own I have hereto affixed my signature in presence of two witnesses.

RICHARD J. NEWMAN.
